Patented Mar. 5, 1968

210,417

VISUAL ACUITY SLIDE PROJECTOR

Paul A. Hoogesteger, Brighton, N.Y., assignor to Bausch & Lomb Incorporated, Rochester, N.Y., a corporation of New York

Filed Aug. 18, 1966, Ser. No. 3,525

Term of patent 14 years

(Cl. D57—1)

FIG. 1 is a front and side perspective view of a visual acuity slide projector, showing my new design; and

FIG. 2 is a rear and opposite side perspective view thereof, to an enlarged scale.

I claim:

The ornamental design for a visual acuity slide projector, substantially as shown.
